[57] CLAIM

The ornamental design for an omnidirectional circularly polarized transmitting antenna, as shown.

DESCRIPTION

FIG. 1 is a top plan view showing my new design for an omnidirectional circularly polarized transmitting antenna;

FIG. 2 is a bottom plan view thereof;

FIG. 3 is a side elevational view thereof;

FIG. 4 is a front elevational view thereof;

FIG. 5 is the other side elevational view thereof; and

FIG. 6 is a rear elevational view thereof.

FIG. 1

FIG. 5

FIG. 6
